UNITED STATES PATENT OFFICE.

MARTIN R. CROSSMAN, OF BOSTON, MASSACHUSETTS.

SOAP-BUBBLER.

1,155,470.

Specification of Letters Patent

Patented Oct. 5, 1915.

Application filed April 6, 1915. Serial No. 19,581.

To all whom it may concern:

Be it known that I, MARTIN R. CROSSMAN, a citizen of the United States, residing at Boston, county of Suffolk, State of Massachusetts, have invented an Improvement in Soap-Bubblers, of which the following description, in connection with the accompanying drawing, is a specification, like characters on the drawing representing like parts.

10 This invention relates to soap bubblers and has for its object to provide a simple soap bubbler provided with means for causing a whistling sound at the time that the bubble is blown, and also constructed so that

15 when the bubbler is not in use the soap-containing end may be covered, thus protecting the soap.

In order to give an understanding of my invention I have illustrated in the drawings 20 a selected embodiment thereof which will now be described, after which the novel features will be pointed out in the appended claims.

In the drawings, Figure 1 is a perspective view of a soap bubbler embodying my invention with a double soap bubble being blown therefrom. Fig. 2 is a side view of the bubbler with the soap-containing end covered; Fig. 3 is a sectional view of the 30 bubbler showing the parts in position for blowing the soap bubble; Fig. 4 is a perspective view of the soap-retaining element.

My improved bubbler comprises a hollow casing 1 which is open at one end, as at 2, 35 the other end 3 being closed except for a small opening 4 formed in the end wall of the casing. Situated in the casing is a removable soap-retaining element 5 herein shown as presenting a pointed end 6 on 40 which a piece of soap 7 may be speared, and a retaining portion 8 which extends into the casing 1 and frictionally engages the wall thereof. This soap-retaining element 5 is also provided with a disk 10 of some frictional material such as rubber, through 45 which the end 6 extends and which engages a laterally-extending portion 9. The disk 10 has frictional engagement with the walls of the casing, and thus serves to frictionally 50 hold the element 5 in place, while permitting it to be readily removed. Said disk is formed on opposite sides with two openings or passages 21 through which the air passes when the bubble is being blown. The soap-retaining element is preferably so constructed 55 that when it is fully inserted into the cas-

ing with the end thereof engaging the end wall 3 of the casing the pointed end 6 of said element 5 will project beyond the open end 2 of the casing so that when the soap 7 is impaled on the end 6 the soap will project beyond the open end of the casing. I will preferably use a piece of soap which has a dimension in one direction equal to the diameter of the open end of the casing, but is narrower in the other direction, thereby leaving two passages 11 and 12 each side of the soap through which the current of air passes when the bubbler is being used.

13 designates a cup-shaped element adapted to telescope over either end of the casing 1. This cup-shaped element constitutes a cap for closing the open end 2 and protecting and covering the soap when the bubbler is not in use, as shown in Fig. 2. When the soap bubbler is to be used this cap 13 is removed from the open end of the casing and then is telescoped over the closed end of the casing, as shown in Figs. 1 and 3. This cap is provided with an opening 14 in its end 70 and when it is placed in position on the casing, as shown in Figs. 1 and 3, with the closed end 15 thereof spaced the proper distance from the end 3 of the casing 1 and a person blows through the aperture 14, a 75 whistling sound will be produced. This results from the relation between the apertures 14 and 4 and the space 16 between the ends 15 and 3. I will preferably provide the casing 1 with an annular rib or stop shoulder 80 90 17 which limits the telescopic movement of the element 13 over the closed end of the tube and positions said element correctly to enable the whistling sound to be produced. When the soap bubbler is in use not only 95 will a whistling sound be produced which adds greatly to the amusement of the person using the device, but the construction is such that a double bubble will be blown, for the air which is blown through the casing 1 100 will be divided into two currents, one passing through each of the passages 11, 12, and each of these air currents will form a separate bubble. The two bubbles will unite at the end of the soap, thus forming a twin or 105 double bubble.

When the device is not in use the cap element 13 can be removed from the closed end and placed over the open end of the casing, thus protecting the soap.

The casing is shown as having a second stop shoulder 18 thereon which positions the

cap 18 when it is placed over the open end 2. By employing the cap 18 the device can be readily carried in the pocket when not in use or can be laid away without danger that 5 the soap will soil any article with which the device comes in contact. The device, therefore, is a sanitary one.

While I have illustrated herein a selected embodiment of my invention I do not wish 10 to be limited to the constructional features shown.

I claim:

1. In a soap bubbler, the combination with a casing having a closed end provided 15 with an aperture and an open end, of a soap-retaining element within said casing and a

cap element adapted to telescope over either end of the casing, said cap element having an aperture in its closed end which when inserted over the closed end of the casing constitutes therewith a whistle. 20

2. In a soap bubbler, the combination with a tubular casing open at one end and provided with an aperture at the other end, of a soap mass inserted into the open end of the 25 casing but projecting beyond said end, said soap mass and casing having such a relative shape as to provide two separate air passages whereby a double bubble will be blown.

In testimony whereof, I have signed my 30 name to this specification.

MARTIN R. CROSSMAN.
